CLAIM

The ornamental design for a jewelry bail, as shown and described.

DESCRIPTION

FIG. 1 is a perspective view of a jewelry bail, showing our new design.

FIG. 2 is a front elevational view;

FIG. 3 is a side elevational view, the opposite side view being a mirror image thereof;

FIG. 4 is a rear elevational view; and,

FIG. 5 is a top plan view.

It being understood that the broken lines in FIG. 4 are for illustrative purposes only and form no part of the claimed design.
